ELECTRIC MOTOR

Hugo Grote, Wetter (Ruhr), Germany, assignor to Demag-Zug G. m. b. H., Wetter (Ruhr), Germany

Application August 10, 1955, Serial No. 37,402

Claims priority, application Germany May 5, 1955

Term of patent 14 years

(Cl. D26—5)

Fig. 1 is a top plan view of an electric motor showing my new design;

Fig. 2 is a side view of the same seen in direction of arrow 2 of Fig. 1;

Fig. 3 is a bottom plan view seen in the direction of arrow 3 of Fig. 2;

Fig. 4 is an end view seen in direction of arrow 4 of Fig. 1; and

Fig. 5 is an end view seen in direction of arrow 5 of Fig. 1.

The dominant features of my design reside in the portion shown in full lines.

I claim:

The ornamental design for an electric motor, as shown and described.
